UNITED STATES PATENT OFFICE

2,451,764

FUSE SETTING APPARATUS

Desmond Walter Molins, Valentine Pearce Harvey, James Arthur Mason, and Gordon Francis Wellington Powell, Deptford, London S. E. 8, England, assignors to Molins Machine Company Limited, Deptford, London S. E. 8, England

Application November 24, 1942, Serial No. 466,803
In Great Britain June 18, 1941

14 Claims. (Cl. 89—6)

1
This invention concerns improvements in or relating to fuze-setting apparatus (for example fuze-setting apparatus for use with anti-aircraft guns), of the kind having an adjustable control member which determines the setting of the movable fuze-element. Usually this control member is a worm-wheel driven by the follow-the-pointer hand-wheel.

The objects of the present invention include a construction whereby the setting of a fuze may be accomplished while the round is supported in a receptacle or the like (e. g. a loading tray) so that immediately the setting operation is finished, the round can be moved towards and into the breech thereby enabling a rapid rate of fire to be attained.

According to the present invention there is provided a fuze-setting apparatus comprising in combination, a fixed stop, an adjustable stop, a gripping device rotatable between said stops to an extent determined thereby and adapted to grip the movable fuze-element of a fuze to be set and arranged to be reciprocated in the direction of its axis of rotation to engage and disengage respectively the movable fuze-element, driving means arranged to be rotated a constant angular amount during each setting operation to reciprocate the gripping device, said driving means being arranged to rotate the gripping device between the end of its outward stroke and the commencement of its return stroke, and a clutch device located between the driving means and the gripping device and arranged to disconnect the rotational drive to the gripping device on engagement with the stop determining the extent of rotation of the gripping device. The clutch may comprise a pivoted pawl member on a driven member of the clutch, a rotatable driving element having a recess to be engaged by the pawl, and means operable on engagement with the stop determining the extent of rotation of the gripping device to move the pawl out of said recess. Means carried by the driving element of the clutch may be provided to engage the pawl on a reverse movement and to rotate the driven member so as to give it a return movement, and in this case an abutment (e. g. the other of the said stops) is arranged to return the pawl into said recess at the end of the said reverse movement. The operating means of the fuze-setter may comprise a plurality of cams which are arranged to control the sequence of operations of the gripping device.

Further according to the invention there is provided in fuze-setting apparatus as set forth in 55 to start.

2
the preceding paragraph and driven by an electric motor, an electrical switch comprising a member axially movable to make the switch and connected to a switch operating member by a toggle, 5 a catch device to hold the axially movable member against movement in the reverse direction and means to bend the toggle joint to break the switch at a predetermined time irrespective of the position of the axially movable member. 10 Means may also be provided to release the catch member at a predetermined time.

One way of carrying the invention into effect will be described with reference to the accompanying drawings in which:

15 Figure 1 is a small scale diagram showing part of a gun on which are mounted a fuze-setter and a loading tray.

Figure 2 is a side elevation, partly in section, 20 of a fuze-setting apparatus construction according to the invention.

Figure 3 is a sectional elevation of Figure 2 taken in the direction of the arrow A.

Figure 4 shows a side elevation of a portion of Figure 2 to a larger scale, and illustrates the 25 clutch and driving devices of the rotatable fuze-setting element.

Figure 5 is an end elevation of Figure 4 taken in the direction of the arrow B.

Figures 6 and 7 are perspective views of two 30 details of the said clutch.

Figures 8, 9 and 10 show details of an electric switch for controlling the driving motor.

Figure 11 is a wiring diagram.

Figure 12 is a fragmentary view of the upper 35 portion of Figure 5, but omitting some of the parts shown in that figure.

Figure 13 is a view similar to Figure 12 but showing the parts in a different position.

Figure 14 is a view similar to Figure 12, but 40 showing the parts in a further different position.

Figure 15 is a perspective view, partly broken away, showing the clutch and its driving gear together with the worm wheel and the adjustable and fixed stops, the parts being in a position occupied when at rest and prior to a setting operation.

Figure 16 is a fragmentary view of the upper part of Figure 14 showing the parts in a position occupied during a setting operation.

Figure 17 is a view generally similar to Figure 50 15 but showing the parts in a different position.

Figure 18 is a view generally similar to Figure 14 but showing the parts in the position occupied when reversal of the driving mechanism is about

Like references refer to like parts throughout the several figures of the drawings.

Referring to the drawings: In Figure 1 there is shown part of a gun and its mounting with the gun-barrel G. B. and the fuze-setter F. S. driven by a motor M and attached to the gun for movement with the barrel about the trunnions T. A loading tray L. T. similarly attached is also shown and a round R is located in the tray ready for the fuze-setting operation. When this is finished the tray is swung about its axis to bring the round into alignment with the breach and then the round is rammed home in the usual way.

In the fuze-setter shown in Figures 2 and 3 by way of example, the fuze-setting apparatus is so arranged that the movable fuze-element of the round is gripped and rotated the desired angular extent by a rotatable gripping device 1, comprising a number of knife edges 2. This device rotates through an arc determined by two stops, but as it is inconvenient to show these stops in Figures 2 and 3, reference should now be made to Figures 4, 5 and 12-18 where it will be seen that the gripping device rotates between a fixed stop 3 and an adjustable stop 4. In Figure 2 the stop 3 is in advance of the section and is therefore shown in chain lines. A movable stop 5 (Figures 4, 5 and 12-18) arranged to engage these other two stops at the extremes of the angular setting movement is mounted for rotation with the gripping device. The fuze-setting apparatus is adapted to be driven by an electric motor 6 or, should this fail, a handle which may be manually operated is provided.

While the movable fuze-element is being rotated, the round is held stationary by a fixed (i. e. non-rotatable) gripping device. This gripping device comprises a number of knives 7 fixed in a member 8 which is supported as hereinafter described. With the particular fuze-setting device shown in the drawing, it is necessary that the movable fuze-element shall be pre-set to a fixed value or angular position relatively to the fixed fuze-element. Normally the movable element is set at "safe."

The fuze-setting device of the apparatus is operated through the medium of a number of cams on a camshaft 9 journalled in the frame 10 of the fuze-setting apparatus and the camshaft is driven from the electric motor 6 by means of reduction gearing, switch arrangements being provided so that the camshaft only rotates one revolution for each setting, this revolution being termed hereafter "a cycle." The shaft of the motor has a pinion 11 at one end which engages with a larger gear-wheel 12 of a compound idler which has another pinion 13 engaging with another large gear-wheel 14 fixed on the camshaft. In order to prevent accidents due to jamming of the fuze-setting apparatus, a clutch device is interposed in the drive from the motor so that should the setter jam, the motor is not injured. This device preferably comprises an arrangement whereby the compound idler swings out of engagement with the other gear-wheels in the event of a jam and is returned manually after the jam has been cleared. As shown in Figure 2, the idler is supported on a pin 15 which is fixed on an arm 16 pivoted at 17. The idler is held in the operative position by a spring 18.

On the camshaft 9 there are provided four cams, one constituting a peripherally grooved drum 19, the other three being simple plate cams to be described later. The grooved cam is ar-

ranged to drive the fuze-setting gripping device which rotates the movable fuze element and which will now be described.

As previously mentioned, the round is placed in the loading tray and immediately this is done the setter operator presses a press button 20 which starts the electric motor. This causes the fuze-setting gripping devices which are supported on a hollow rotatable sleeve 30 to approach towards the fuze of the shell until such time as the fixed and moving gripping devices engage with the tapered surface of the fuze and are jammed against it. The outline of the end of the setting device is shown in the forward position in Figure 2 by chain lines, but not to scale. As the grooved cam rotates, it oscillates a double-arm lever 21 mounted on a fixed pivot 22 in the setter frame and furnished at the end of one arm with a roller 23 running in the groove 24 of the cam. The end of the other arm of the lever is of quadrant shape and furnished with gear teeth 25 which engage with a pinion 26 mounted on another fixed shaft 27. A gear-wheel 28 is fixed to this pinion and engages with a ring gear-wheel 29 which is concentric with, and loosely mounted on, the hollow sleeve 30 and which is adapted to drive the rotatable setting device through a clutch. This clutch is shown more clearly in Figures 4, 5 and 12-18 which will now be referred to again.

The ring gear-wheel 29 has attached concentrically therewith a driving disc 31 forming the driving element of the clutch and having an arcuate recess 32 in its periphery and a projection 33 on the leading side of the recess when the ring gear-wheel is moving in the forward or fuze-setting direction, that is in the direction (indicated by the arrow C, Figures 5 and 13) in which it is rotated when the movable stop 5 is moving from the fixed stop 3 to the adjustable stop 4. The driven element of the clutch comprises a disc 34 formed on a hub concentric with, and splined to, the hollow sleeve 30, see Figure 4. The disc 34 has a lobe or lug 35 in which is pivotally mounted a rocking pawl device 36 constructed as follows. The pawl is formed as shown in Figure 5 as a bent double-armed lever or bell crank fixed on the squared end 37 of a stud 38 pivotally mounted in the lobe 35 of the driven disc 34, and the extremities of the two arms 36a and 36b of the bell-crank are shaped to coincide with arcs struck from the pivotal axis as illustrated in the figure. The arcuate recess 32 is concentric with the axis of the bell-crank and is of just sufficiently greater radius than the arc of the extremity of the arm 36a of the bell-crank to allow the arm 36a to move in the recess. The driving disc 31 has another concave arc 39 in its periphery which is of slightly greater radius than, and which is struck from the same centre as, the extremity of the other arm 36b of the bell-crank. The movable stop 5 is formed integrally with the stud 38, see Figure 6, and is in the shape of a block and is so arranged as to engage the adjustable stop 4 at the end of the forward or setting movement, see Figures 12 and 13. The block is so shaped that when it engages the adjustable stop, the pawl 36 is rocked so that the arm 36a, which then lies in the recess 32 in the forward or setting movement, is brought clear of the recess as shown in Figures 5 and 17. The driving disc 31 is thus free to continue to rotate in the direction of the arrow C leaving the driven disc 34 of the clutch stationary. The driv-

ng disc moves in this direction for a distance sufficient to allow the longest possible fuze-setting to be accomplished wherever the adjustable stop may be. The extreme possible position of the adjustable stop 4 is shown in chain lines near the left hand bottom part of Figure 5. After the disc 31 has moved this distance (see Figure 18), the driving disc is moved in the reverse direction (i. e. as shown by the arrow D) by the reverse movement of the double arm lever 21 operated by the grooved cam 19.

A pivoted catch pawl 40 is provided to hold the movable stop 5 against the adjustable stop 4 when the former engages the latter in order to enable the movable stop and consequently the driven disc to move with the adjustable stop if the latter is moving in response to the indications of the receiver needle of the predictor. The pawl 40 which is shown in perspective in Figure 7 has two pins 41 forming pivots which are located in holes in the body of a wormwheel 42 and an arcuate plate 43 screwed into a recess in said wheel. The pawl is provided with a tail 44 at one end which is engaged by a compression spring 45, Figures 5, 12 and 14. The other end of the pawl has a hook 46 which is engaged by the movable stop 5 and forced upwardly thereby as shown in Figure 13, and then snaps over the movable stop 5 under the pressure of the spring 45, when the pawl takes up the position shown in chain lines in Figure 5, and more clearly shown in Figures 12 and 17. The pawl is further provided with an arcuate lug 47 which acts as a cam follower, for when the projection 33 on the disc 31, on its reverse movement, passes beneath said lug, it raises the pawl against the pressure of the spring 45 into the position shown in Figure 14, and thus releases the movable stop 5 from control of the hook 46.

On the reverse movement of the disc 31 the projection 33 on the driving disc also engages the arm 36b of the bell-crank when the projection 33 on the driving disc returns into contact with the bell-crank just after releasing the stop 5 from the hook 46 as mentioned above. Continued reverse movement of the driving disc thereafter rotates the driven disc 34 in the direction of the arrow D and brings the movable stop 5 (or if desired the bell-crank) ultimately into engagement with the fixed stop 3. This latter is so shaped that on such engagement the bell-crank will be turned so that the first arm 36a thereof again enters the recess 32 in readiness for the next cycle. See Figure 15, and also the lower part of Figure 5 where the bell-crank is shown in broken lines (two dots and a dash) thus turned and ready for the next setting.

The body or mounting 48 which rotatably supports the fuze setting gripping devices and to which the non-rotatable member 8 of the round gripping device is fixed has attached thereto a guide rod 49 which slides in bushes 50 in the frame of the setting apparatus and it is reciprocated to and fro at the necessary times by means of a lever 51 having a forked end 52 provided with rollers 53 engaging a circumferential groove 54 formed in a collar on the outside of the inner end of the hollow sleeve 30 which carries at its outer end the rotatable gripping device of the fuze-setting apparatus. The lever 51 is loosely mounted on a shaft 55 pivoted to the frame of the setting apparatus and to this shaft there is also fixed a bell-crank lever 56 having cam rollers 57 and 58 on its free ends. These rollers engage cams 59 and 60 comprising two of the previously

mentioned plate cams mounted on camshaft 9. The cams are so shaped that the fuze-setting gripping devices are positively reciprocated to and fro at the necessary times. In order to accommodate varying positions of the noses of rounds, the lever 51 which engages the groove in the rotatable gripping device is coupled to the shaft 55 by means of a spring cushion arrangement permitting the lever 51 a restricted degree of movement with respect to the shaft sufficient to allow for the above variation. As shown, one arm of the bell-crank lever 56 houses a spring 61 which is located at its other end in a recess in the lever 51. A stud 62 prevents the levers from separating and also provides means whereby the spring 61 may be adjusted.

The adjustable stop 4 is formed as a projection on the arcuate plate 43 which is fixed to the wormwheel 42 which latter is concentric with and embraces the hollow sleeve 30 of the fuze setting gripping devices. This wormwheel is engaged by a worm 63 fixed to a shaft 64. A bevel gear wheel 65 on the shaft 64 engages another bevel gear wheel 66 on a shaft 67 which receives its movement in the usual manner from a fuze-setting hand wheel (not shown) rotated by the operator who watches the receiver dial.

The operation of the apparatus so far described is as follows: A round is placed in the loading tray and the operator presses the button 20 which starts the electric motor and immediately the camshaft starts rotating. One of the plate cams which operates the lever 51 engaging the grooved collar on the fuze-setting gripping devices causes these devices to slide in the guides previously mentioned until the gripping devices of the apparatus engage a fuze of the round as previously mentioned. Normally this operation, from the moment the switch is pressed, takes one quarter of a second. At the completion of this interval the grooved cam 19 has rotated sufficiently far to cause the gearing which drives the gripping device 1 for the movable element of a fuze, to start operating and this gripping device moves through a distance determined by the angular displacement of the adjustable stop 4 with respect to the fixed stop 3. As soon as the movable stop 5 engages the adjustable stop 4, the clutch in the drive for the rotatable gripper 1 operates to release the driven disc 34 but the driving disc 31 completes its movement as previously described and as shown in Figures 17 and 18. The reverse movement of the rotatable gripping device is timed to commence only after the member or head 8 carrying the gripping devices has moved back away from the movable fuze-element.

As soon as the head 8 is clear of the round the loading tray is moved up to carry the round in front of the breech. A latch arrangement is provided to lock the loading tray against movement until the fuze-setting gripping devices are clear of the round.

While these operations are taking place it will be understood that the man watching the receiver pointer is constantly turning his hand wheel to follow the pointer and thus the worm wheel 42 of the setting apparatus which carries the adjustable stop 4 is constantly on the move, and the gripping device 1 moves with it since the stops 4 and 5 are locked together by the catch pawl 40 as shown in Figure 13. Thus up to the moment when the knives of the gripping device are disengaged from the fuze, the angular displacement given to the fuze corresponds with the movements of the pointer.

At the end of a cycle, that is one revolution of the camshaft, the motor is stopped and the apparatus is ready for the next shell. It will be apparent that the stopping must occur at a predetermined time so that the camshaft rotates only one revolution per cycle.

The stopping of the motor is performed by a switch which is operated at the desired instant from the camshaft in the following manner: On the camshaft 9 is fixed a disc 68 having a pin 69 which is fixed in one face thereof and which at the correct time strikes a pivoted lever 70 fixed on a spindle 71 journalled in the frame 10 as shown in Figure 9. To this spindle 71 there is also fixed a detent or pawl 72. The pawl or detent 72 may be angularly adjustable relatively to the lever.

The stopping switch is the same switch as the press button starting switch and consists of an ordinary switch contact arrangement comprising spring contacts 73 and 74, Figure 9. The contacts 73 are attached to a switch operating member 175 and the switch can be "made" and "broken" by axial movements of a rod 75. The rod has a groove 76 in it, or any equivalent abutment with which the detent 72 can engage, and when the press button 20 is pushed in, the switch "makes" and the detent catches in the groove and holds the switch in the "on" position against the action of a spring 77. When the pin 69 in the disc 68 strikes the lever 70 the detent is lifted and the rod 75 could ordinarily be returned by the spring 77. But as the time of a cycle is so short it may well happen that the setter operator might still be pressing on the button at the end of a cycle, in which case the motor would not stop. To prevent such an occurrence, the rod 75 is specially constructed and embodies a knee-joint or toggle 78, see Figures 9 and 10, with which it is connected to the switch operating member 175. This toggle is so arranged, assisted, if desired, by springs, that the parts 75, 78 and 175 all normally form a rigid rod, and when the button 20 is pressed the rod moves axially as a rigid member. To ensure the positive breaking of the switch irrespective of pressure on the button 20 a lever 79 fixed to the shaft 71 is arranged to engage the toggle from one side and bend it, whereupon the spring 77 causes the contact 73 to move to the left as seen in Figure 9, thus breaking the switch.

Referring now to the wiring diagram, Figure 11, as the apparatus is intended for use in the field, the motor, which is preferably compound wound, may be driven by a battery B which in the example being described is a 24 volt storage battery. To assist in rapidly stopping the motor at the end of a cycle, means may be provided whereby the motor is caused to act as a generator as the switch is broken. For this purpose, one line from the battery leads to the press button switch 20 and through said switch to the coils of a contactor C and a shunt field relay S. F. R. in parallel therewith, to the other line and back to the battery. The first line also passes on beyond the button switch terminal to the motor through the series field S. F. and armature A and to one contact of the contactor, being tapped between the press button switch terminal and the series field by lines leading to a second contact of the contactor and to one terminal of the shunt field Sh. F. respectively. The other end of the shunt field is connected to one contact of the shunt field relay and the second contact of said relay is connected to the other pole of the

battery, being tapped en route for the other ends of the contactor and shunt field relay coil and for a line leading to a third contactor contact. The fourth contactor contact is joined to the first contact. A condenser and resistance are shunted across the shunt field relay contact.

When the press button is pushed, the moving contact bar of the contactor is connected to the first and third contacts and the shunt field is energised by the shunt field relay so that the motor runs as a compound motor. When the button switch is broken the contactor bar moves back by spring pressure to the second and fourth contacts (i. e. the upper pair in Figure 11) and the series field and armature are short circuited. Meanwhile the shunt field is still energised due to the delay action incorporated in the shunt field relay, so that the back E. M. F. of the motor flowing through the low impedance of the armature and series field gives instant and heavy regenerative braking; after a period of say half a second the shunt field relay opens and the shunt field is removed.

Should it prove impossible to drive the apparatus by the motor owing to a failure in the circuit, or an exhausted battery, the setter may be operated manually. For this purpose a hand crank 80 may be fixed on to the camshaft 9, as shown in Figure 3. To ensure that the camshaft is only turned a single revolution per cycle when manually operating, a spring pressed abutment or stop 81 is fixed to the frame at a position corresponding to the beginning and end of the revolution and this stop latches into a spring plunger 82 of square cross-section in the crank arm. As the operator grasps the crank handle to operate the apparatus he presses the knob 83 of the spring plunger with his thumb to release the crank from the spring stop. For this purpose the plunger is slotted at a position such that it clears the stop when the plunger is pressed in. It is, however, impossible to maintain the thumb pressure during an entire revolution as the hand twists round on the crank handle so the plunger springs out again and when it meets the spring stop at the end of the revolution the parts lock together again until the plunger is pressed once more.

What we claim as our invention and desire to secure by Letters Patent is:

1. Fuze-setting apparatus comprising the combination of a rotatable fuze-engaging element mounted for axial reciprocation into and out of setting engagement with the movable fuze-element of a round, a fixed stop whose position determines the beginning of rotational setting movement of the fuze-engaging element, an adjustable control member, a stop which is carried by said adjustable control member and whose momentary position determines the end of rotational setting movement of the fuze-engaging element, rotatable driving means, means operable to stop said driving means after the latter has rotated a predetermined constant amount, means operated by said driving means for reciprocating the fuze-engaging element, and means driven by the driving means to rotate the fuze-engaging element to set the fuze after the fuze-engaging element has reached the end of its outward stroke and before the commencement of its return stroke, said driven means comprising a clutch device having a movable member adapted to engage the stop carried by the adjustable control member and to be moved there-

by to break the rotational drive to the fuze-engaging element.

2. Fuze-setting apparatus comprising the combination of a rotatable fuze-engaging element mounted for axial reciprocation into and out of setting engagement with the movable fuze-element of a round, a fixed stop whose position determines the beginning of rotational setting movement of the fuze-engaging element, an adjustable control member, a stop which is carried by said adjustable control member and whose momentary position determines the end of rotational setting movement of the fuze-engaging element, rotatable driving means, means operable to stop said driving means after the latter has rotated a predetermined constant amount, means operated by said driving means for reciprocating the fuze-engaging element, means driven by the driving means to rotate the fuze-engaging element to set the fuze after the fuze-engaging element has reached the end of its outward stroke and before the commencement of its return stroke, said driven means comprising a clutch device having a movable member adapted to engage the stop carried by the adjustable control member and to be moved thereby to break the rotational drive to the fuze-engaging element, and a locking device carried by the adjustable control member adapted to engage and to be moved by the movable member at the end of a setting movement of the fuze-engaging element to lock the latter to the stop carried by the adjustable control member, whereby subsequent to the breaking of the rotational drive and before the return stroke of the fuze-engaging element, any further movements of the control member are imparted to the fuze-engaging element.

3. Fuze-setting apparatus as claimed in claim 2, wherein said locking device comprises a latch carried by the adjustable control member and adapted to engage a part rotatable with the fuze-engaging element to couple said element to the adjustable control member when the clutch is disconnected.

4. Fuze-setting apparatus comprising the combination of a rotatable fuze-engaging element mounted for axial reciprocation into and out of setting engagement with the movable fuze-element of a round, a fixed stop whose position determines the beginning of rotational setting movement of the fuze-engaging element, an adjustable control member, a stop which is carried by said adjustable control member and whose momentary position determines the end of rotational setting movement of the fuze-engaging element, rotatable driving means, means operable to stop said driving means after the latter has rotated a predetermined constant amount, means operated by said driving means for reciprocating the fuze-engaging element, means driven by the driving means to rotate the fuze-engaging element to set the fuze after the fuze-engaging element has reached the end of its outward stroke and before the commencement of its return stroke, said driven means comprising a clutch device including a driven member carrying a pivoted pawl, a rotatable driving element having a recess to be engaged by the pawl, and means operable by engagement with the stop carried by the adjustable control member to move the pawl out of said recess and thereby to break the rotational drive to the fuze-engaging element.

5. Fuze-setting apparatus comprising the combination of a rotatable fuze-engaging element

mounted for axial reciprocation into and out of setting engagement with the movable fuze-element of a round, a fixed stop whose position determines the beginning of rotational setting movement of the fuze-engaging element, an adjustable control member, a stop which is carried by said adjustable control member and whose momentary position determines the end of rotational setting movement of the fuze-engaging element, rotatable driving means, means operable to stop said driving means after the latter has rotated a predetermined constant amount, means operated by said driving means for reciprocating the fuze-engaging element, means driven by the driving means to rotate the fuze-engaging element to set the fuze after the fuze-engaging element has reached the end of its outward stroke and before the commencement of its return stroke, said driven means comprising a clutch device including a driven member carrying a pivoted pawl, a rotatable driving element having a recess to be engaged by the pawl, a movable member carried by said pawl, said movable member being operable by engagement with the stop carried by the adjustable control member to move the pawl out of said recess and thereby to break the rotational drive to the fuze-engaging element, and a locking device carried by the adjustable control member adapted to engage and to be moved by the movable member at the end of a setting movement of the fuze-engaging element to lock the latter to the adjustable control member, whereby subsequent to the breaking of the rotational drive and before the return stroke of the fuze-engaging element, further movements of the adjustable control member are imparted to the fuze-engaging element.

6. Fuze-setting apparatus comprising the combination of a rotatable fuze-engaging element mounted for reciprocation into and out of setting engagement with the movable fuze-element of a round, a fixed stop whose position determines the beginning of rotational setting movement of the fuze-engaging element, an adjustable control member, a stop which is carried by said adjustable control member and whose momentary position determines the end of rotational setting movement of the fuze-engaging element, rotatable driving means, means operable to stop said driving means after the latter has rotated a predetermined constant amount, means operated by said driving means for reciprocating the fuze-engaging element, means driven by the driving means to rotate the fuze-engaging element to set the fuze after the fuze-engaging element has reached the end of its outward stroke and before the commencement of its return stroke, said driven means comprising a clutch device including a driven member carrying a pivoted pawl, a rotatable driving element having a recess to be engaged by the pawl, means operable by engagement with the stop carried by the adjustable control member to move the pawl out of said recess and thereby to break the rotational drive to the fuze-engaging element, means carried by said driving element to engage with the pawl on a reverse movement and to rotate said driven member so as to give it a return movement, and an abutment to return the pawl into said recess at the end of the said reverse movement.

7. Fuze-setting apparatus comprising the combination of a rotatable fuze-engaging element mounted for axial reciprocation into and out of

setting engagement with the movable fuze-element of a round, a fixed stop whose position determines the beginning of rotational setting movement of the fuze-engaging element, an adjustable control member, a stop which is carried by said adjustable control member and whose momentary position determines the end of rotational setting movement of the fuze-engaging element, rotatable driving means, means operable to stop said driving means after the latter has rotated a predetermined constant amount, means operated by said driving means for reciprocating the fuze-engaging element, means driven by the driving means to rotate the fuze-engaging element to set the fuze after the fuze-engaging element has reached the end of its outward stroke and before the commencement of its return stroke, said driven means comprising a clutch device including a driven member carrying a pivoted pawl, a rotatable driving element having a recess to be engaged by the pawl, means movable with the fuze-engaging element operable by engagement with the stop carried by the adjustable control member to move the pawl out of said recess and thereby to break the rotational drive to the fuze-engaging element, a locking device carried by the adjustable control element adapted to engage and to be moved by the said last named means at the end of a setting movement of the fuze-engaging element to lock the latter to the adjustable control member, whereby subsequent to the breaking of the rotational drive and before the return stroke of the fuze-engaging element, any further movements of the adjustable control member are imparted to said fuze-engaging element, means carried by said driving element to engage with the pawl on a reverse movement and to rotate said driven member so as to give it a return movement, and an abutment to return the pawl into said recess at the end of the said reverse movement.

8. Fuze-setting apparatus comprising the combination of a rotatable fuze-engaging element mounted for axial reciprocation into and out of setting engagement with the movable fuze-element of a round, a fixed stop whose position determines the beginning of rotational setting movement of the fuze-engaging element, an adjustable control member, a stop which is carried by said adjustable control member and whose momentary position determines the end of rotational setting movement of the fuze-engaging element, rotatable driving means, means operable to stop said driving means after the latter has rotated a predetermined constant amount, means including a cam device and operated by said driving means for reciprocating the fuze-engaging element, and means including cam means driven by the driving means to rotate the fuze-engaging element to set the fuze after the fuze-engaging element has reached the end of its outward stroke and before the commencement of its return stroke, said driven means comprising a clutch device having a movable member adapted to engage the stop carried by the adjustable control member and to be moved thereby to break the rotational drive to the fuze-engaging element.

9. Fuze-setting apparatus comprising the combination of a rotatable fuze-engaging element mounted for axial reciprocation into and out of setting engagement with the movable fuze-element of a round, a fixed stop whose position determines the beginning of rotational setting movement of the fuze-engaging element, an ad-

justable control member, a stop which is carried by said adjustable control member and whose momentary position determines the end of rotational setting movement of the fuze-engaging element, rotatable driving means including an electric motor, a switch automatically operable to stop said driving means after the latter has rotated a predetermined constant amount, said switch comprising a member axially movable in one direction to make the switch, a switch-operating member, a toggle connecting the latter to the axially movable member, a catch device to hold the switch-operating member against movement in the reverse direction, and means movable in timed relationship with the driving means to bend the toggle joint to break the switch when the motor has rotated a predetermined amount irrespective of the position of the switch-operating member, means operated by said driving means for reciprocating the fuze-engaging element, and means driven by the driving means to rotate the fuze-engaging element to set the fuze after the fuze-engaging element has reached the end of its outward stroke and before the commencement of its return stroke, said driven means including a clutch device having a movable member adapted to engage the stop carried by the adjustable control member and to be moved thereby to break the rotational drive to the fuze-engaging element.

10. Fuze-setting apparatus as claimed in claim 9, wherein means is provided to release the catch device at a predetermined time.

11. Fuze-setting apparatus comprising in combination of a rotatable fuze-engaging element mounted for axial reciprocation into and out of setting engagement with the movable fuze-element of a round, a fixed stop whose position determines the beginning of rotational setting movement of the fuze-engaging element, an adjustable control member, a stop which is carried by said adjustable control member and whose momentary position determines the end of rotational setting movement of the fuze-engaging element, rotatable driving means, a power unit to actuate said driving means, means operable to stop said driving means after the latter has rotated a predetermined constant amount, means operated by said driving means for reciprocating the fuze-engaging element, means driving by the driving means to set the fuze after the fuze-engaging element has reached the end of its outward stroke and before the commencement of its return stroke, said driven means comprising a clutch device having a movable member adapted to engage the stop carried by the adjustable control member and to be moved thereby to break the rotational drive to the fuze-engaging element, and a clutch device between the said power unit and said driving means so constructed and arranged as to automatically break the drive from said power unit to said driving means if a jam occurs in the apparatus.

12. Fuze-setting apparatus as claimed in claim 11, wherein a gearing is provided through which said power unit actuates the driving means and the clutch device comprises an idler gear forming part of said gearing which swings out of engagement with said gearing when a jam occurs in the setting mechanism.

13. Fuze-setting apparatus comprising the combination of a rotatable fuze-engaging element mounted for axial reciprocation into and out of setting engagement with the movable fuze-ele-

ment of a round, a fixed stop whose position determines the beginning of rotational setting movement of the fuze-engaging element, an adjustable control member, a stop which is carried by said adjustable control member and whose momentary position determines the end of rotational setting movement of the fuze-engaging element, rotatable driving means, means operable to stop said driving means after the latter has rotated a predetermined constant amount, 10 means operated by said driving means for reciprocating the fuze-engaging element, and means driven by the driving means to rotate the fuze-engaging element to set the fuze after the fuze-engaging element has reached the end of its outward stroke and before the commencement of its return stroke, said driven means comprising a clutch device having a movable member adapted to engage the stop carried by the adjustable control member and to be moved thereby to break the rotational drive to the fuze-engaging element, said driving means comprising a manually operable element and said stopping means comprising a device for stopping said manually operable element at the end of a cycle.

14. Fuze-setting apparatus as claimed in claim

13, wherein the manually operable element comprises a hand-crank and said device comprises a catch for preventing movement of the crank until said catch is released by pressure of the thumb or a finger, said catch being thereafter spring urged into the operative position when said pressure is relaxed upon the continued rotational movement of the crank.
